UNITED STATES PATENT OFFICE.

HENRY G. COX, OF DETROIT, MICHIGAN.

MAGNETO-BATTERY SWITCH.

1,033,786.

Specification of Letters Patent. Patented July 30, 1912.

Application filed March 16, 1911. Serial No. 614,764.

To all whom it may concern:

Be it known that I, HENRY G. COX, a citizen of the United States, residing at Detroit, in the county of Wayne and State of Michigan, have invented a new and useful Magneto-Battery Switch, of which the following is a specification.

In the operation of internal combustion engines, especially of the type commonly in use in automobiles, the ignition is accomplished by means of electric sparks produced either from a battery or a magneto generator, and the object of my invention is to produce a switch of such form that it may be readily and accurately operated by foot in such manner that either battery or magneto may be connected with or disconnected from the distributing circuit and also of such character that, when in battery connecting position, slight additional pressure will bring into operation a vibrator which will operate to produce a continuous stream of sparks within that particular engine cylinder connected by the distributor with the ignition circuit.

The accompanying drawings illustrate my invention.

Figure 1 is a front elevation of one form of the improved switch, with the cover plate removed, and with a wiring diagram; Fig. 2 a section on line 2—2 of Fig. 1; Fig. 3 a section on line 3—3 of Fig. 1; Fig. 4 a front elevation of the apparatus with the cover in place; and Fig. 5 a sectional view of a detail.

In the drawings, 10 indicates a cup-like base preferably formed of insulating material and conveniently triangular in shape. Rising from the bottom of base 10 are three pins 11, 12 and 13, each of which is provided with a semi-spherical enlargement 14 at its base. The three pins 11, 12 and 13 are arranged at the middles of the sides of the base 10 and sleeved over said pins is a triangular metal switch frame 15, each side of which is perforated, as indicated at 16, to receive one of the pins. Each of the perforations 16 has a semi-spherical seat at its inner end to receive one of the enlargements 14, the construction being such that the frame 15 may be readily rocked in any one of three directions upon any pair of pins. Carried at the apices of frame 15 are push buttons 17, 18 and 19 which project from the frame 15 preferably through a suitable cover plate 21. The frame 15 is preferably open in its center in order to give space for the

mounting of a vibrating coil 22 in the bottom of the cup-like base 10 with the usual terminals 23 and 24 for the vibrating terminal 25. Projecting from that apex of the frame 15 which carries button 17, are two fingers 26 and 27. Finger 26 is adapted to co-operate with a terminal 28 which is preferably formed by a pair of spring fingers between which the finger 26 may be yieldingly retained. Finger 27 co-operates with a similar terminal 29. Projecting from that apex of frame 15 which carries button 18, is a finger 31 which is adapted to co-operate with a terminal 32. Projecting from that apex of frame 15 which carries button 19 is a finger 33 arranged to co-operate with a retainer 34. The terminals 29 and 32 and retainer 34 may be like terminals 28. Projecting from the apex which carries the push button 18 is an arm 35 adapted to engage an insulating button 36 carried by a spring terminal 37 secured in the bottom of the base 10, and this terminal 37 is adapted, when sufficiently depressed, to contact with a terminal 38.

In order that the device may be readily rendered inactive I mount the push button 19 removably and rotatably in the frame 15, and provide said button with a projecting key 41 which may be first introduced into slot 42 in frame 15 and then turned into slot 43 of said frame so as to drive a spring terminal 44, attached to, and in electrical contact with, frame 15, into contact with a terminal 45 mounted in the cup 10. In use, this contact being maintained in all positions of frame 15, the apparatus will be set in front of the operator, either upon the floor or upon the dash board of the car in such position that the operator may engage any one of the push buttons 17, 18 or 19 and operate the same by a direct leg push. I prefer to mount the apparatus substantially vertically on the dash board with the button 19 uppermost. The following wiring connections are then made:—From one side of battery 51 by a wire 52 to terminal 32 and from the other side of battery 51 by wire 53 to terminal 28; wire 54 from terminal 28 to terminal 23; wire 55 from terminal 24 to one end of the coil of the vibrator 22, and wire 56 from the other end of said coil to terminal 37; wire 57 from wire 53 (or terminal 28) to the insulated terminal 58 of the usual interrupter 59 carried by the magneto 61; by wire 62 from the

ungrounded terminal 63 of the magneto to terminal 29; wire 64 from the terminal 65 of the spark coil 66 to the grounded terminal 67 of the magneto; wire 68 from terminal 38 to terminal 65, and wire 69 from the primary terminal 71 of the spark coil 66 to terminal 45.

The operation is as follows: An insertion of the button 19 into its proper place in frame 15 to the position shown in Fig. 1, will serve to bring into contact the terminals 44 and 45, thus putting the frame 15 into the primary circuit. A pressure upon the button 19 will cause the frame 15 to swing upon pins 11 and 13 as a fulcrum so as to drive finger 33 into the retaining engagement of the member 34 so as to hold frame 15 in its neutral position. In this position of frame 15 both the battery and magneto circuits are broken. By exerting a pressure upon button 18, frame 15 will swing upon pins 12 and 13 as a fulcrum so as to withdraw finger 33 from retainer 34 and drive finger 31 down into engagement with terminals 32 where it will be yieldingly retained so as to complete the battery circuit 51, 52, 32, 31, 15, 44, 45, 69, 71, 65, 64, 67, 58, 57, 58. If a starting spark is desired the operator will press hard enough upon button 18 to drive the spring terminal 37 into contact with terminal 38, whereupon a circuit will be established from battery 51 through 53, 28, 54, 23, 25, 24, 55, 22, 56, 37, 38, 68, 65, 71, 69, 45, 44, 15, 31, 32 and 52 so that by reason of the action of the vibrator 22, a rapid succession of sparks will be automatically produced in whichever cylinder is in proper condition to receive a spark from the secondary circuit 81. As soon as the engine is started, the additional pressure upon frame 15 will be withdrawn so as to permit terminal 37 to withdraw from terminal 38, and the movement of the engine will rotate the magneto and interrupter. Thereafter so long as the frame 15 remains in the position indicated, the sparking circuit will be as previously described.

Whenever the magneto has reached a desired and proper generating speed, the operator will then press upon button 17 so as to swing frame 15 upon pins 11 and 12 thereby withdrawing finger 31 from terminal 32 and projecting fingers 26 and 27 into contact with terminals 28 and 29, respectively, whereupon the following circuits will be established: (1) At the times when the points in the interrupter box are in engagement the circuit will be, 63, 62, 29, 27, 15, 26, 28, 57, 58, generator 63. (2) At the times when the points in the interrupter box are not in engagement the circuit will be, 63, 62, 29, 27, 15, 44, 45, 69, 71, 65, 64, 67, generator, 63.

It is desirable at times to be able to de-

liver a stream of sparks to the engine while the operator is in front of the machine "crawling" it and for that purpose, I provide a push button 91 which is mounted in the main body 10. This push button is normally urged outwardly by a spring 92 and at its inner end carries a spring terminal 93 which, at its tip is formed into a catch 93' adapted to cooperate with a terminal 94 which is secured to and in electrical contact with terminal 37. The terminal 93 is connected by a wire 95 with wire 68 and at its inner end is provided with a tip which, when frame 15 is depressed by operation upon button 18, will overlie the frame, as clearly indicated in Fig. 5. The terminals 93, 94 thus form a parallel around the two terminals 37, 38, when terminals 93, 94 are in contact and the same results may then be attained as may be attained by a sufficient pressure upon button 18 to bring terminal 37 into contact with terminal 38. When pressure is applied to button 17, however, frame 15 will engage the tip 93' of terminal 93, raise it from engagement behind terminal 94, and spring 92 will serve to drive the terminal 93 away from terminal 94.

I claim as my invention:

1. A switch comprising two sets of independent circuit terminals, a terminal controlling member, a flexible support for said controlling member permitting tilting movement of said controlling member into three different positions by application of force in the same general direction but upon different portions of said member, and means carried by said controlling member and coöperating with the independent circuit terminals for independently opening and closing said independent circuits.

2. A switch comprising two sets of independent circuit terminals, a terminal controlling member, a flexible support for said controlling member permitting tilting movement of said controlling member about different axes into three different positions, and means carried by said controlling member and coöperating with the independent circuit terminals for independently opening and closing said independent circuits.

3. A switch comprising a controller member having a multiplicity of supporting axes each arranged at an angle to the other and about any of which said controller member may be swung from any position, and independent circuit terminals arranged in position to be independently controlled by said controller member when swung upon its different axes.

4. A switch comprising three supporting points arranged in a triangle, a controlling member flexibly mounted upon said three points and tiltable upon the three axes formed by the point triangle, and two inde-

pendent sets of circuit terminals each arranged in position to be closed by a movement of the controlling member upon one of its axes and opened by movement of the controlling member upon either of the other axes.

5. A switch comprising three supporting points arranged in a triangle, a controlling member flexibly mounted upon said three points and tilttable upon the three axes formed by the point triangle, and two independent sets of circuit terminals each arranged in position to be closed by a movement of the controlling member upon one of its axes.

10. 6. A switch comprising three supporting points arranged in a triangle, a controlling member flexibly mounted upon said three points and tilttable upon the three axes formed by the point triangle, two independent sets of circuit terminals each arranged in position to be closed by a movement of the controlling member upon one of its axes and opened by movement of the controlling member upon either of the other axes, a pair of normally separated terminals, and means carried by the controlling member for contacting said normally separated terminals.

15. 7. A switch comprising three supporting points arranged in a triangle, a controlling member flexibly mounted upon said three points and tilttable upon the three axes formed by the point triangle, two independent sets of circuit terminals each arranged in position to be closed by a movement of the controlling member upon one of its axes, a pair of normally separated terminals, and means carried by the controlling member for contacting said normally separated terminals.

20. 8. A switch comprising a substantially triangular controller member, a three-axis support for said controller member, two circuit terminals arranged to be contacted by movement of the controller member upon one of its axes, a circuit terminal arranged to be contacted by the controller member when swung upon another of its axes, a pair of normally separated terminals arranged to be contacted by further movement of the controller member when contacted with said last mentioned terminal, and a circuit terminal normally in contact with the controller member in all of its positions.

25. 9. A switch comprising a substantially triangular controller member, a three-axis support for said controller member, two circuit terminals arranged to be contacted by movement of the controller member upon one of its axes, a circuit terminal arranged to be contacted by the controller member when swung upon another of its axes, and a circuit terminal normally in contact with the controller member in all of its positions.

30. 10. A switch comprising a substantially

triangular controller member, a three-axis support for said controller member, two circuit terminals arranged to be contacted by movement of the controller member upon one of its axes, a circuit terminal arranged to be contacted by the controller member when swung upon another of its axes, a pair of normally separated terminals arranged to be contacted by further movement of the controller member when contacted with said last mentioned terminal, another terminal carried by a support adjacent the controller member, and a key removably mounted upon the controller member and arranged to establish contact between said last mentioned terminal and the controller member in all of its positions.

35. 11. A switch comprising a substantially triangular controller member, a three-axis support for said controller member, two circuit terminals arranged to be contacted by movement of the controller member upon one of its axes, a circuit terminal arranged to be contacted by the controller member when swung upon another of its axes, another terminal carried by a support adjacent the controller member, and a key removably mounted upon the controller member and arranged to establish contact between said last mentioned terminal and the controller member in all of its positions.

40. 12. A switch comprising a controller member, a flexible support for said controller member permitting tilting movement about different axes into three different positions by application of force in the same general direction but upon different portions of said member, two sets of independent circuit terminals, and means carried by said controller member and coöperating with the independent circuit terminals for independently opening and closing said independent circuits.

45. 13. A switch comprising two sets of independent circuit terminals, a terminal controlling member, a flexible support for said controlling member permitting tilting movement of said controlling member about different axes into three different positions, and means carried by said controlling member and coöperating with the independent circuit terminals for independently opening and closing said independent circuits.

50. 14. A switch comprising a movable member supported at three points located at the apices of a triangle and movable about any side of said triangle as an axis, and contact members coöperating with said movable member.

55. 15. A switch comprising a movable member supported at a plurality of points located at the apices of the angles of a polygon and movable about different sides of said polygon as axes, and contact members coöperating with said movable member.

16. A switch comprising a polygonal movable member supported at a plurality of points located at the corners of a polygon inscribed within the polygon formed by 5 said movable member, said movable member being movable about different sides of said inscribed polygon as axes, and contact members coöperating with different corners of said movable member.
- 10 17. A switch comprising a polygonal movable member provided with holes in its various sides, fixed pins extending loosely into said respective holes and loosely supporting said movable member so that the 15 latter may move about different pairs of the pins, and contact members coöperating with said movable member.
18. A switch comprising a polygonal movable member provided with holes in its various sides, fixed pins extending loosely 20 into said respective holes and loosely supporting said movable member so that the latter may move about different pairs of the pins, and contact members coöperating with different corners of said movable member. 25

In witness whereof, I have hereunto set my hand and seal at Detroit, Michigan, this 7th day of March, A. D. one thousand nine hundred and eleven.

HENRY G. COX. [L.s.]
